No. 608,990.

Patented Aug. 9, 1898.

J. B. McCUTCHEON.

ATTACHMENT FOR PNEUMATIC STACKERS.

(Application filed Dec. 23, 1896. Renewed June 29, 1898.

(No Model.)

UNITED STATES PATENT OFFICE.

JOHN B. MCCUTCHEON, OF BATTLE CREEK, MICHIGAN.

ATTACHMENT FOR PNEUMATIC STACKERS.

SPECIFICATION forming part of Letters Patent No. 608,990, dated August 9, 1898.

Application filed December 23, 1896. Renewed June 29, 1898. Serial No. 684,759. (No model.)

To all whom it may concern:

Be it known that I, JOHN B. MCCUTCHEON, a citizen of the United States, residing at Battle Creek, in the county of Calhoun and State of Michigan, have invented new and useful Improvements in Attachments for Pneumatic Stackers, of which the following is a specification.

This invention relates to attachments to pneumatic stackers used in connection with threshing-machines. In a pneumatic stacker or "wind-stacker," as more commonly called, the strong draft caused by the blast of air is liable to carry off more or less grain with the straw; and it is the object of my invention to avoid this waste or loss of grain and convey it to a suitable receiver.

My invention consists in features of construction and novel combinations of parts in a wind-stacker attachment for threshing-machines, as hereinafter described and claimed.

In the annexed drawings, illustrating the invention, Figure 1 is a vertical longitudinal section of my improved wind-stacker attachment. Fig. 2 is a vertical cross-section of the same.

Referring to the drawings, the numeral 1 designates what may be termed the "inner" tube or section of a telescopic chute 2, which 30 comprises also an outer tube or section 3, the one tube being arranged to have a sliding adjustment with relation to the other. On the innermost end of the tube 1 is a collar 4 and in one end of the tube 3 is a collar 5, the said collars 4 and 5 being so disposed as to center the tube 1 in the tube 3 and permit sliding adjustment of the said tubes or telescopic sections without great friction, and these collars 4 and 5 also serve as stops to 40 prevent disconnection of the telescopic tubes when drawn out to full extent. At a suitable point on the tube 1 is a collar 6, which serves as a stop to limit inward or shortened adjustment of the telescopic tubes. The 45 outer end of the tube 1 is curved downward and has attached thereto an adjustable curved elbow 7, which constitutes the inlet to the telescopic chute and is to be placed in such proximity to the threshing-machine as to receive the straw that is carried off by the air-blast. To permit adjustment of the elbow 7, it may have a hinged connection 8 with the

lower end of a yoke 9, that is secured to the tube 1 of the telescopic chute. In the upper end of the yoke 9, above the tube 1, is journaled a pulley 10, to which is attached one end of a rope or flexible connection 11, which is passed over a guide-roller 12 and secured at its outer end to a lug 13 on the farther end of the telescopic tube 3. The guide- 60 roller 12 may be supported above the yoke 9, as shown. By rotating the pulley 10, to which a winch-handle may be connected, the rope 11 will be wound on said pulley and thereby draw together the tubes 1 and 3, so as to 65 shorten the telescopic chute. The outer end of the tube 3 is open at its under side to form an outlet 14 for discharge of straw. To guard this outlet, there is secured to the end of the tube 3 a downwardly-curved hood 15, 70 that is provided with an adjustable section 16, which is hinged at 17, as shown.

In most pneumatic stackers considerable grain is carried off with the straw and cannot be readily recovered. For the purpose 75 of avoiding this waste of grain I have provided means for separating the straw from such grain as may be carried with it into the straw-chute and to conduct the saved grain to a suitable receptacle. As a means for accomplishing this result there is hinged at 18 in one end of the straw-outlet 14 a series of fingers 19, that extend across the somewhat funnel-shaped inlet end 20 of an adjustable grain-spout 21, which is hinged or pivoted at 85 the same point as said fingers. The spout 21 is extended backward beneath the telescopic chute 2, and it is adjustably supported at or near its rear end by means of sliding connections 22 and 23, which may consist of bars or 90 rods connected by a set-screw 24 or otherwise, the upper bar being arranged to have a pivotal connection 25 with the under side of the main or outer chute-section. The rear end of the spout 21 is curved downward to form 95 a grain-outlet 26, through which the grain will be discharged into any suitable receptacle.

In passing out from the chute the straw is deflected upward toward the top of the tube 3 by means of the fingers 19, while any grain 100 that may have been carried out to that point will fall between the said fingers into the inlet end of the grain-spout 21 and be thereby conducted to a suitable receiver. This

stacker attachment can be readily adjusted to varying requirements of threshing-machines and will effect a large saving of grain that has been hitherto lost with the straw.

- 5 What I claim as my invention is—
1. In a pneumatic stacker for threshing-machines, the combination with a straw-chute having an outlet in the under side of its outer end, of an adjustable grain-spout having an enlarged inlet end in communication with the said chute-outlet and hinged to the rear side thereof, and a series of fingers hinged at the same point as the adjustable grain-spout and extended across the inlet to the said spout, substantially as described.
  - 15 2. In a pneumatic stacker for threshing-machines, the combination of a telescopic

straw-chute having an outlet in the under side of its outer end, an adjustable grain-spout having its inlet end in communication with the chute-outlet and hinged thereto, a series of fingers hinged at the same point as the grain-spout and extended across its inlet, and adjustable connections between the rear portions of the straw-chute and said grain-spout, substantially as described.

In testimony whereof I have hereunto set my hand in presence of two subscribing witnesses.

JOHN B. McCUTCHEON.
